PAUL E. FENTON, OF THOMASTON, CONNECTICUT, ASSIGNOR TO SCOVILL MANUFACTURING COMPANY, OF WATERBURY, CONNECTICUT, A CORPORATION OF CONNECTICUT

MACHINE-ATTACHED RIVET AND BURR

Application filed August 13, 1929. Serial No. 385,649.

There is a preference in the garment trade for special fastenings of the rivet and burr type which are truly handset or applied in a good simulation of hand setting. This 5 preference is not without merit, in that such setting begets in the consumer a confidence of excellence of workmanship and the correspondingly gratifying prospect of durability and long wear.

10 These rivet and burr fasteners are applied at a number of points of stress and strain in garments and are more or less conspicuous

In riveting cloth garments it occurs frequently that the fibres or threads of the cloth 15 are dislodged or loosened and carried by the leading end of the driven rivet through the hole in the burr or washer and exposed on the outside, thereby giving an unsightly appearance which detracts from the saleability of 20 the garment by offending the fancy of the buyer.

The present invention consists of a machine-attached rivet and burr, which in being attached closely simulates hand setting and 25 which will not disturb the fibres or threads of the fabric, as I will proceed now more particularly to explain and finally claim.

In the accompanying drawings illustrating 30 the invention, in the several figures of which like parts are similarly designated, Figure 1 is a bottom plan view and Fig. 2 a vertical cross section of the burr. Fig. 3 is an elevation of a form of rivet or tack that may be and preferably is used in connection with the burr. Fig. 4 shows the burr in cross section 35 and the tack in elevation on opposite sides of plies of fabric. Fig. 5 is a view similar to Fig. 4, in which the tack is driven through the plies of fabric and is ready to enter the burr. Fig. 6 is a section showing the burr and tack set upon plies of fabric.

40 All of the views show the parts enlarged.

Instead of a burr made as a flat annulus, like an ordinary washer, I use a structure 45 having a flat laterally extending flange 1, from the center of which is drawn a cylindrical barrel 2 having a closed and inwardly or upwardly depressed end 3, having the relatively inclined rim 4. Instead of a blunt-pointed rivet I prefer to use a sharp-pointed

tack, Fig. 3 having the flat head 5 and pointed shank 6.

The burr and tack may be of suitable metal, such that when they are arranged upon or machine-fed to opposite sides of parts to be 55 united, the tack will pierce the parts 7 and also pierce the closed end of the burr and pass up into the barrel of the burr, and then upon force being applied the barrel of the burr will enter the fabric without fraying or loosening its threads or fibres and sink into the 60 fabric and be held by clinching the shank of the tack, as illustrated in Fig. 6.

In other words, the burr and tack function 65 in a self-piercing manner, without drawing the threads or fibres of the material to which they are applied up through the hole in the burrs made by the tack. When the burr and tack are assembled in a setting machine, the point of the tack registers with the depressed closed end of the barrel of the burr and 70 pierces through the metal a hole always the exact size of the shank of the tack or rivet, so that there is no room for the threads of the material to be drawn up through the hole; and when the burr and tack are assembled or 75 set, the finish is entirely free from protruding threads or fibres, and closely approaches hand-riveting.

Variations in details of construction are 80 permissible within the principle of the invention and the claims following.

What I claim is:—

1. A burr provided with a flange and a barrel extending from said flange and having a closed and inwardly depressed end, and a rivet or tack having a pointed shank adapted to be driven through the closed end of the barrel and clinched therein, the clinching of the rivet or tack making a hole in the burr no 85 larger than its shank and thereby preventing the drawing through and exposing of the threads or fibres of the material.

2. A burr provided with a flange and a barrel extending from said flange and having a closed and inwardly depressed end, and a rivet or tack having a pointed shank adapted to be driven through the closed end of the barrel and clinched therein, the clinching of the rivet or tack making a hole in the burr 90 95 100

no larger than its shank and thereby preventing the drawing through and exposing of the threads or fibres of the material, the barrel being sunk in the material.

5 In testimony whereof I have hereunto set my hand this 12th day of August, A. D. 1929.

PAUL E. FENTON.
